R. S. Allaire, ATTORNEY

UNITED STATES PATENT OFFICE

JOHN MILTON GLADISH, OF LAGRANGE, GEORGIA, ASSIGNOR TO VALWAY RUG MILLS, INCORPORATED, OF LAGRANGE, GEORGIA, A CORPORATION OF GEORGIA

TUFTING MACHINE LOOPER AND CUTTER

Application filed October 2, 1929. Serial No. 396,715.

This invention relates to looping and cutting mechanism for tufting machines and has for its object to increase the speed of operation of such machines thereby increasing 5 their productivity and worth.

A further object is to reduce the likelihood of bending and breaking needles from their engagement with a substantially heavy or rigid looper as has heretofore been the 10 practice and also to reduce the likelihood of not forming a tuft for each stroke of the needle.

Referring to the drawing, Fig. 1 shows the relative position of the looper and needle 15 as the needle is moving downward.

Fig. 2 shows the needle near the end of its downward stroke.

Fig. 3 shows the engagement of the looper between the needle and strand, the needle 20 moving upwardly.

Fig. 4 shows the position of the looper for cutting the strand with the needle above the work.

Fig. 5 is a left end view with the needle 25 and looper in the position illustrated in Fig. 3.

Fig. 6 shows a specimen of the work with some of the tufts cut and others not cut, the tufts being longer than is customary for the 30 sake of clearness of illustration.

Fig. 7 is a section on the line of 7-7 of Fig. 10.

Fig. 8 is a section on the line of 8-8 of Fig. 10.

Fig. 9 is a top plan view of the looper in the position shown in Fig. 3.

Fig. 10 is a detail view showing the construction of the looper and its mounting.

The needle 12 is provided with the usual 40 eye 13 through which the strand 14 is passed and the needle also has a recessed and flattened portion 15 to enable the loop forming means or looper 16 to engage between the strand and needle to hold the strand and form 45 a loop as the needle rises. The needle is operated by any suitable prior art mechanism. The work is fed through the machine by any suitable type feed mechanism, not shown.

Unlike previous tufting machines the present invention contemplates a looper 16 which

is yieldably mounted and is comparatively thin. In fact the looper 16 in practice is made from a portion of a flexible safety razor blade and formed into the shape illustrated. The combined looper and cutter is soldered 55 to the support 23a without drawing the temper in the cutter. The blade 16 is formed by breaking or cutting a flexible razor blade into four parts each provided with a sharp cutting edge and then dulling a portion of 60 the edge to form the looper and shaping the blade to the form shown. On account of its flexibility it is desirable to provide stationary guides 17 between which the looper passes adjacent the needle. 65

These guides are supported from some convenient stationary portion of the machine.

In Fig. 2 the looper 16 is about to engage the strand and needle while in Fig. 3 the looper has engaged the strand and the needle is 70 moving upwardly. In this position the looper preferably holds the strand until the needle passes above the work, the longitudinal motion of the looper being preferably arrested

for an interval sufficient to permit the needle 75 to clear the goods. The portion of the looper engaging the strand in Fig. 3 has a dull under edge, as shown in Fig. 7. Immediately

back of this looper portion the under edge of the flexible member is sharpened as shown 80 in Fig. 8 to constitute a cutter for the strand. On moving the looper further into the strand as shown in Fig. 4 the sharpened lower edge of Fig. 8 engages the strand and cuts it. Subsequently the looper is retracted to the position

shown in Fig. 1 ready for reengagement 85 with the needle and strand on the next descent of the needle.

Fig. 6 shows uncut loops 19 as well as cut loops 20 extending from the work 18. 90

The loops shown by Fig. 6 are somewhat larger than would be customary in order to more clearly show how the present invention is adapted for forming either type loops.

Figs. 9 and 10 show one type of mounting 95 for the combined looper and cutter of this invention in which the slideable lever 21 supports the looper and cutter through the post 23. The portion of the looper and cutter in back of the cutting edge is provided with one 100

or more serrations 22 for the purpose of withdrawing any lint from between the guides 17. As shown in Fig. 10, the head 23a mounted on the post 23 has the flexible looper 5 and cutter secured thereto in some convenient manner as for example, by soldering to the flat face of the head 23a. By controlling the extent of movement of the combined looper and cutter into the strand, this element may 10 be effective to cut or not cut the loops as desired.

When forming uncut loops the looper need only engage the strand and not pull it down substantially, since the upward travel of the 15 needle holds the strand tight enough to form uniform length of tufts. For engaging the sharp edge of the looper and cutting the tufts, a slight downward movement is desirable. Also the inclined lower edge of cutter 16 facilitates cutting and is another reason why less 20 up and down motion for the cutter is needed in the present invention than has heretofore been usual.

To form loops of different lengths the 25 looper 16 may be given a greater up and down travel as is customary.

The looper should upon reaching a position like that illustrated in Fig. 3, hold the strand on the dull lower edge until the needle is 30 above the work after which the strand can be moved rearwardly with respect to the looper to engage the sharp cutting edge.

As shown in Fig. 5 the eye 13 of the needle 35 12 is in substantial alignment with the stitching. None of the usual strand gripping means are as necessary as has been the case heretofore, although if desired, some customary type of such strand gripping means may be employed as a means of more certainly 40 insuring precise uniformity in the length of the tufts. Any customary type work support not shown may be provided.

The flexibility of the looper does not endanger breaking the needle, in fact the looper 45 may strike the needle without danger since it is deflected without harm. The combined looper and cutter in the present invention are more compact than any prior combination of looper and cutter. There are several functions 50 for the combined looper and cutter of this invention. It acts as a loop retainer to hold the strand during the upward travel of the needle. It may or may not cut the strand. It takes out lint from between the guides. It 55 flexes and can bend aside when it strikes the needle. It makes the use of strand grippers less necessary to tuft length uniformity although such may be used if desired.

The operating units described may be used 60 together in any desirable number.

This application is a continuation in part of my prior application Serial No. 290,977 filed July 7th, 1928.

I claim:

65 1. The method of making a combined

looper and cutter which comprises dividing a flexible razor blade, dulling a portion of an edge to form a looper and securing said divided part of the razor blade to a support, all of said operations being performed without dulling or drawing the temper of the cutter portion.

2. The method of making a tufting machine 70 flexible looper which comprises dividing a flexible razor blade, rounding an end and at least a portion of an edge adjacent said end and securing said blade portion to a support for attachment to a tufting machine.
